UNITED STATES PATENT OFFICE.

RAYMOND MOYER TATE, OF PLYMOUTH, ENGLAND.

APPARATUS FOR PLAYING GAMES OF SKILL.

Application filed April 21, 1924. Serial No. 707,888.

To all whom it may concern:

Be it known that I, RAYMOND MOYER TATE, of Plymouth, England, a subject of the King of Great Britain and Ireland, have invented certain new and useful Improved Apparatus for Playing Games of Skill, of which the following is a specification.

This invention relates to apparatus for playing games of skill.

An apparatus made in accordance with this invention comprises a stationary base or table, a rotatable post or the like projecting vertically upwards from about the centre of said base, means for rotating the post or the like, an arm extending horizontally therefrom, a model figure carried at or near the outer end of the arm, one or more objects placed on the table in proximity to the path of the model figure, a pivoted member on the model figure the free end of which is adapted to engage the said objects, means for normally holding the pivoted member so that the free end clears the said objects and means for moving the pivoted member at will into and out of engagement with the objects as the post or the like is rotated. Means may also be provided whereby the displacement of an object automatically stops the rotation of the post. Also, electric or other means may be provided for giving an audible or visual warning that an object on the base has been displaced.

One form of apparatus constructed in accordance with this invention is shown in the accompanying drawings, which are to some extent diagrammatic.

Fig. 1 shows a front elevation;

Fig. 2 shows a side elevation;

Fig. 3 shows a plan, of the apparatus so constructed;

Fig. 4 is a diagram of the wiring.

The apparatus consists of a circular railing or barrier *a* within which is a circular table *b*, and a vertical post *c* in the centre of the table. A balanced horizontal arm *d* is pivoted on ball or other bearings to the post *c* and carries at one of its ends a small electric motor *e* driving an air-screw *f*, and at its other end a rigidly suspended figure *g* made to resemble a rider with a lance *h*. Round the table *b* are placed models *j j* of animals or other objects, and the lance and the arm of the model rider are pivoted and are normally held in such a position that

the lance clears the objects *j j* when the figure *g* is revolved with the arm *d*.

Below the arm *d* and attached thereto there is a disc *k* and a corresponding disc *m*, and brushes *n n* attached to the latter disc bear lightly on a series of contact segments *o o* attached to the former disc. Leads are taken from the segments to two electromagnets which are arranged to draw the pivoted arm of the model rider in opposite directions. Hand-operated switches or push-knobs *p p* are provided whereby the players can supply electric current to the segments *o o*.

The arrangement of the segments *o o* and of the brushes *n n* is such that if a switch is depressed when the lance *h* is very close to one of the objects *j j*, both of the electromagnets which actuate the lance are excited and one of these electromagnets has more turns than the other and thus overcomes the said other electromagnet and draws the lance *h* down, causing it to strike one of the objects *j*. If the switch *p* is depressed too soon, only one of the electromagnets is excited and the lance is thrown upwards, the opposing magnet, which is excited immediately afterwards, becoming inoperative by the displacement of the armature which actuates the lance.

The objects *j j* may be of metal and may be so arranged that when normally placed they bridge contacts in the circuit of a relay which causes an electric bell or an electric horn to sound when an object is displaced and at the same time, by any suitable means, causes the rotating post *c* to be stopped.

Fig. 4 shows a diagram of one manner in which the wiring of this apparatus can be arranged. 1, 2, are the terminals for supplying current to the apparatus, 3 is the electric motor which drives the air screw, 4, 5, 6 are segments, 7, 8, 9 the brushes and 10, 11 two of the switches or push knobs. 12 is the winding of the magnet which raises the lance, 13 the winding of the magnet which lowers the lance. 14, 15, 16 are three of the contacts which are normally bridged by the feet of the objects, 17 is a relay actuating the electric signal horn 18 when the circuit is broken at any of these contacts. 19 and 20 are switches adapted respectively to stop the motor 3 and silence the signal horn 18.

The apparatus is principally intended for construction on a fairly large scale for the

use of from about twelve to, say, thirty-six players, and is adapted for use at fairs and the like gatherings. Any convenient source of electric energy may be used in connection therewith.

What I claim and desire to secure by Letters Patent is:—

1. Apparatus for playing a game of skill comprising a stationary base or table, a post 10 projecting vertically upwards from about the centre of the said table, an arm extending horizontally therefrom, means for rotating the said arm, a model figure carried near the outer end of the arm, an object 15 placed on the table in proximity to the path of the model figure, a pivoted member on the model figure the free end of which is adapted to engage the said object, means for normally holding the pivoted member so that the free end clears the said object, and means for moving the pivoted member at will into and out of engagement with the object as the arm is rotated.
2. Apparatus for playing a game of skill 20 comprising a stationary table, a post projecting vertically upwards from about the centre of the said table, an arm extending horizontally therefrom, means for rotating the said arm comprising an electric motor 25 attached thereto and an air-screw driven by the said motor, a model figure carried near the outer end of the arm, an object placed on the table in proximity to the path of the model figure, a pivoted member on the 30 model figure the free end of which is adapted to engage the said object, means for normally holding the pivoted member so that the free end clears the said object and for moving the pivoted member at will into and out of engagement with the object as the arm is rotated, the said means comprising two 35 unequally wound electromagnets adapted to act on an iron arm attached to the said member and a contact connected to the said magnets, adapted to be worked by a player and sliding contact members whereby the electric current for this latter purpose and for driving the air-screw is led to the arm.
3. Apparatus for playing a game of skill 40 comprising a stationary table, a post projecting vertically upwards from about the centre of the said table, an arm extending horizontally therefrom, means for rotating the said arm comprising an electric motor 45 attached thereto and an air-screw driven by the said motor, a model figure carried near the outer end of the arm, an object placed on the table in proximity to the path of the model figure, contacts normally 50 bridged by the said object, a relay connected to the said contacts, an electric alarm adapted to be actuated through the said relay by the removal of the object from the contacts, electrically operated means whereby the removal of the object cuts off the power from the electric motor and stops the arm, a pivoted member on the model figure the free end of which is adapted to engage the said object, means for normally 55 holding the pivoted member so that the free end clears the said object and for moving the pivoted member at will into and out of engagement with the object as the arm is rotated, the said means comprising two unequally wound electromagnets adapted to act on an iron arm attached to the said member and a contact connected to the said magnets, adapted to be worked by a player and sliding contact members whereby the 60 electric current for this latter purpose and for driving the air-screw is led to the arm.

the outer end of the arm, an object placed on the table in proximity to the path of the model figure, contacts normally bridged 60 by the said object, a relay connected to the said contacts, an electric alarm adapted to be actuated through the said relay by the removal of the object from the contacts, a pivoted member on the model figure 65 the free end of which is adapted to engage the said object, means for normally holding the pivoted member so that the free end clears the said object and for moving the pivoted member at will into and out of 70 engagement with the object as the arm is rotated, the said means comprising two unequally wound electromagnets adapted to act on an iron arm attached to the said member and a contact connected to the said magnets, adapted to be worked by a player and sliding contact members whereby the 75 electric current for this latter purpose and for driving the air-screw is led to the arm.

4. Apparatus for playing a game of skill 80 comprising a stationary table, a post projecting vertically upwards from about the centre of the said table, an arm extending horizontally therefrom, means for rotating the said arm comprising an electric motor 85 attached thereto and an air-screw driven by the said motor, a model figure carried near the outer end of the arm, an object placed on the table in proximity to the path of the model figure, contacts normally 90 bridged by the said object, a relay connected to the said contacts, an electric alarm adapted to be actuated through the said relay by the removal of the object from the contacts, electrically operated means whereby the removal of the object cuts off the power from the electric motor and stops the arm, a pivoted member on the model figure the free end of which is adapted to engage the said object, means for normally 95 holding the pivoted member so that the free end clears the said object and for moving the pivoted member at will into and out of engagement with the object as the arm is rotated, the said means comprising two 100 unequally wound electromagnets adapted to act on an iron arm attached to the said member and a contact connected to the said magnets, adapted to be worked by a player and sliding contact members whereby the 105 electric current for this latter purpose and for driving the air-screw is led to the arm.

In testimony whereof, I affix my signature.
RAYMOND MOYER TATE.
